(57) **CLAIM**

The ornamental design for a water pump adaptor, as shown and described.

DESCRIPTION

FIG. 1 is a top perspective view of a water pump adaptor;
FIG. 2 is a bottom perspective view of a water pump adaptor;
FIG. 3 is a bottom view thereof;
FIG. 4 is a top view thereof;
FIG. 5 is a front view thereof;
FIG. 6 is a rear view thereof;
FIG. 7 is a right view thereof;
FIG. 8 is a left view thereof;
FIG. 9 is top perspective view thereof, showing environmental use of the claimed design;
FIG. 10 a cross-section view along 11 of FIG. 4;
FIG. 11 is cross-section view along 10 of FIG. 4; and,
FIG. 12 is a cross-section view along 12 of FIG. 4.
The broken lines shown in FIG. 9 are included for illustrating an environmental structure and form no part of the claimed design.
